United States Patent Office

Des. 193,442
Patented Aug. 21, 1962

193,442

BRACELET LINK OR SIMILAR ARTICLE

Murray L. Cowan, Boston, Mass., assignor to Speidel Corporation, Providence, R.I., a corporation of Rhode Island

Filed June 22, 1961, Ser. No. 65,690

Term of patent 14 years

(CL. D45—4)

FIG. 1

FIG. 4

FIG. 1 is a perspective view of a bracelet link or similar article showing my new design; and

FIG. 2 is a side elevational view thereof;

FIG. 3 is a top plan view thereof; and

FIG. 4 is a front elevation taken looking from right to left at FIG. 2.

The essential features of my design reside in the portions shown in full lines.

I claim:

The ornamental design for a bracelet link or similar article, substantially as shown and described.
